UNITED STATES PATENT OFFICE.

JESSE A. HEYDRICK, OF BARNHART'S MILLS, PENNSYLVANIA.

PUMP.

SPECIFICATION forming part of Letters Patent No. 269,414, dated December 19, 1882.

Application filed July 14, 1882. (No model.)

To all whom it may concern:

Be it known that I, JESSE A. HEYDRICK, of Barnhart's Mills, in the county of Butler and State of Pennsylvania, have invented a new and Improved Pump, of which the following is a full, clear, and exact description.

The invention consists in a pump formed of a rotary vertical cylinder attached to the lower end of a rotary stand-pipe, which cylinder contains a reciprocating piston provided with downwardly-projecting shanks or prongs resting on spiral tracks, whereby the piston will be reciprocated and water raised when the pump-tube and the cylinder are rotated. The piston is provided with a downwardly-projecting perforated pipe within a perforated pipe connected with the spiral tracks.

The invention further consists in an inverted cylindrical cup attached to the upper end of the stand-pipe, into which cup a tubular projection projects, which forms part of a vessel surrounding the inverted cup.

The invention also consists in certain parts, and of constructions and combinations of the same, as will be fully described hereinafter.

Reference is to be had to the accompanying drawings, forming part of this specification, in which similar letters of reference indicate corresponding parts in all the figures.

Figure 1 is a longitudinal sectional elevation of my improved pump. Fig. 2 is a longitudinal elevation of the cylinder, partly in section. Fig. 3 is a longitudinal sectional elevation of a modification of the same.

The pump-cylinder A is attached to the lower end of the stand-pipe B, which extends down to near the bottom of the well or cistern. The cylinder A is closed at the top and bottom, and contains the vertically - reciprocating solid plunger or piston C, which is provided with two downwardly-projecting spirally-curved prongs or shanks, D, which project through the slots D' at the periphery of the bottom A' of the cylinder. The piston is provided in its interior and at the upper end with a downwardly-projecting cup-shaped valve-box, E, containing a ball-valve, F, adapted to close the central aperture, F', of the cup-shaped box E. The upper end of the piston or plunger C is provided with a cup-shaped recess, G, containing a ball-valve, H, which is adapted to close the upper end of the longitudinal aper-

ture H' of the piston. A perforated tube, J, projects downward from the bottom of the cylinder A, and is provided at its lower end with a step, J', resting on a bearing formed at the lower end of a perforated tube, K, surrounding the tube J, which tube K is fixed and held rigidly in the bottom of the well or cistern. To this tube K a horizontal disk is attached, which is provided with two annular concentric vertical spiral cam tracks or ridges, M M, which have their highest and lowest points, respectively, directly opposite each other—that is, the starting-points of the spiral tracks are diametrically opposite each other, and as the highest point of each spiral track is adjoining to its starting, the highest points will also be diametrically opposite each other. The lower ends of the prongs or shanks D rest on the spiral tracks M, Fig. 3, or spiral track-pieces N, Fig. 2, attached to the lower ends of the prongs or shanks D, rest on the tracks M.

Above ground a horizontal bevel cog-wheel, O, is rigidly mounted on the tube A, and rests on rollers P, journaled in the upper ends of the standards Q of the pump-frame. A bevel cog-wheel, R, provided with a crank-handle, R', engages with the bevel cog-wheel O. An inverted cylindrical cup, S, is attached to the upper end of the tube A, and rests on the upper edge of a tubular projection, T, of a closed vessel, U, surrounding the cup S, and provided with an outlet pipe or spout, V, which vessel U rests on the pump-frame. The tubular projection T passes up between the pipe B and the cup S.

The operation is as follows: To raise water the crank-handle R' is turned, whereby the wheel O, the stand-pipe B, the cylinder A, the piston C, and the tube J will be rotated. The lower ends of the prongs or shanks D, or the track-sections N, pass over the tracks M when the cylinder A is rotated, and as the tracks M are spiral the piston C will be reciprocated vertically once for every time the tube B is rotated. When the piston C rises a vacuum is produced between the bottom of the piston and the bottom of the cylinder, and the water passes into the vacuum through the perforated tubes J K. When the piston descends, the water in the cylinder raises the ball H and passes above the piston, and when the piston rises the water is forced upward, raises the ball

F, and passes into the tube B, through which it rises into the vessel U and flows through the spout V. As the cup S rests upon the upper edge of the tubular projection T, it forms a close joint, which prevents the water from flowing over the upper edge of the tubular projection T.

This pump can be operated with comparatively little power, it raises a large quantity of water, is not apt to get out of order, as no sucker-rod is required, and the handle-lever can be dispensed with.

The cylinder A can be made any desired suitable size, as circumstances may require.

15 The pump can also be used as a force-pump to throw water upward from the spout V.

Having thus described my invention, what I claim as new, and desire to secure by Letters Patent, is—

20 1. In a pump, the combination, with fixed cam-tracks, of rotating cylinder closed at top and bottom and fixed to the lower end of the stand-pipe, and a piston within said cylinder, provided with shanks or prongs projecting 25 downwardly through the bottom of the said cylinder and running on the said cam-tracks, substantially as herein shown and described, whereby the piston will be reciprocated as the cylinder is revolved, as set forth.

30 2. In a pump, the combination, with the stand-pipe B, the rotating cylinder A, having a slotted bottom and fixed to the lower end of said stand-pipe, and the fixed cam-tracks M, of the reciprocating piston C, revolving with 35 said cylinder, and provided with downwardly-projecting shanks or prongs D, substantially as herein shown and described, and for the purpose set forth.

3. In a pump, the combination, with the vertical rotary cylinder A and the stand-pipe B, to the lower end of which it is attached, of the reciprocating piston C, provided with downwardly-projecting prongs or shanks D, the fixed spiral tracks M, the perforated tube J, 45 projecting from the lower end of the cylinder A, and of the perforated tube K, surrounding the tube J, and connected with tracks M, substantially as herein shown and described, and for the purpose set forth.

4. In a pump, the combination, with the vertical rotary cylinder A and the stand-pipe B, to the lower end of which the cylinder A is attached, of the reciprocating piston C, the prongs or shanks D, and the track-pieces N, attached to the lower ends of the same, and 55 the spiral tracks M, secured in the lower part of the well, on which tracks M the track-pieces N rest, substantially as herein shown and described, and for the purpose set forth.

5. In a pump, the combination, with the rotary stand-pipe B and the cylinder A, attached to the lower end of the same, of the reciprocating piston C, located in the cylinder, and provided in its top with a recess, G, containing a ball-valve, H, the cup-shaped valve-box 65 E in the top of the cylinder, and containing a ball-valve, F, the prongs or shanks D, projecting from the lower end of the piston, and the fixed spiral tracks M, substantially as herein shown and described, and for the purpose set 70 forth.

6. In a pump, the combination, with the rotary stand-pipe B, the rotary cylinder A, attached to the lower end of the same, and the reciprocating piston C in the cylinder, of the inverted cup S, attached to the upper end of the stand-pipe, and the vessel U, provided with an internal tubular projection, T, projecting into the cup S, substantially as herein shown and described, and for the purpose set 80 forth.

7. In a pump, the combination, with the rotary stand-pipe B, the rotary cylinder A, attached to the lower end of the same, and the reciprocating piston C in the cylinder A, of 85 the inverted cup S, attached to the upper end of the stand-pipe, the vessel U, provided with an internal tubular projection, T, the bevel cog-wheel O, rigidly mounted on the stand-pipe, and the bevel cog-wheel R, engaging with 90 the bevel cog-wheel O, and provided with a crank-handle, R', substantially as herein shown and described, and for the purpose set forth.

JESSE A. HEYDRICK.
